UNITED STATES PATENT OFFICE.

ABRAHAM DEYO AND WILLIAM S. SCHROEDER, OF CHICAGO, ILLINOIS.

CAR-COUPING.

SPECIFICATION forming part of Letters Patent No. 412,879, dated October 15, 1889.

Application filed May 14, 1889. Serial No. 310,728. (No model.)

To all whom it may concern:

Be it known that we, ABRAHAM DEYO and WILLIAM S. SCHROEDER, citizens of the United States, residing at Chicago, in the county of 5 Cook and State of Illinois, have invented certain new and useful Improvements in Car-Couplings, of which the following is a full, clear, and exact description, that will enable others to make and use the same, reference 10 being had to the accompanying drawings, forming a part of this specification.

The object of this invention is to provide an automatic or gravity locking attachment to be used in connection with the ordinary 15 interlocking coupling-hooks, as will be hereinafter set forth.

Figure 1 is part section and part side elevation, the sectional part being in plane 1, Fig. 2, lengthwise of the draw-bar, showing 20 the head end and coupling-hook in elevation, looking in the direction indicated by the arrow; and Fig. 2, a horizontal longitudinal section.

Referring to the drawings, A represents 25 the draw-bar; B, the head or enlarged end; C, the coupling hook, and C' the pivot-pin securing the hook C to the head end of the draw-bar. The locking-lever D is arranged longitudinally in the chamber D' of the draw- 30 bar, and is provided vertically with the elongated aperture a, for the insertion of the pin or bolt a', which passes through the top and bottom of the draw-bar and secures the locking-lever in proper relative position with reference to the draw-bar and coupling-hook. The lugs a² a³, formed on and projecting inwardly from the side or cheek a⁴ of the draw- 35 bar, provide against a lateral movement of the locking-lever. The inside bottom of the draw-bar is provided with the raised rounded seating-surface b. By this arrangement the locking-lever is adapted to have a rocking movement in a vertical plane.

To the rear end of the lever D is connected 45 the inner upper end of the link b', the lower end of which projects through the opening b² in the under side of the draw-bar, as shown in Fig. 1. The projecting end of the link b' is provided with the aperture b³ for the attachment of any suitable means extending 50 inwardly from both sides of the car, whereby the lever D may be conveniently thrown out of a locking engagement when uncoupling.

The inner end of the coupling-hook is provided with the beveled surface b⁴, on which 55 the outer or locking end of the lever D rides when the coupling-hook swings on its pivot in the act of uncoupling. Normally the locking end of the lever D lies in the pathway of the inner end of the coupling-hook, 60 which moves in the plane of a circle.

The head of the draw-bar is provided at one side with the chamber d, in which is seated the coiled spring d', bearing against the back edge of the coupling-hook, and 65 serves the purpose of automatically throwing the inner end of the hook outwardly when the locking end of the lever is raised, and thereby conveniently disengaging the companion hooks. 70

When companion coupling-hooks are made to engage or interlock, the outer end of the lever D automatically drops down into the locking position and prevents the coupling-hooks from being accidentally thrown 75 out of engagement. The outer end of the hook has the aperture d² and the recess d³, which provide for coupling with a draw-bar having the ordinary link and pin.

Having thus described our invention, what 80 we claim as new, and desire to secure by Letters Patent, is—

1. The combination, with the draw-bar, of the locking-lever chambered therein and provided near the back end with an elongated 85 aperture, the pivot-pin passing through said aperture and the link secured to said lever and projecting through the under side of the draw-bar, substantially as and for the purpose set forth. 90

2. The combination, with the draw-bar provided on the inside with the raised rounded seat and inwardly-projecting lugs, of the locking-lever chambered in said draw-bar, whereby said lever is adapted to have a rocking 95 movement in a vertical plane, but prevented from moving laterally, substantially as and for the purpose set forth.

ABRAHAM DEYO.
WILLIAM S. SCHROEDER.
